UNITED STATES PATENT OFFICE.

JAMES L. EWIN, OF WASHINGTON, DISTRICT OF COLUMBIA.

IMPROVEMENT IN STREET-LIGHTING APPARATUS.

Specification forming part of Letters Patent No. 151,109, dated May 19, 1874; application filed May 2, 1874.

To all whom it may concern:

Be it known that I, JAMES LITHGOW EWIN, of the city and county of Washington, in the District of Columbia, have invented a new and useful Improvement in Street-Lighting Apparatus, of which the following is a specification:

This invention relates primarily to a certain type of street-lamps in which oil is burned instead of illuminating-gas, the oil being supplied to the burner from a large tank or reservoir beneath the lantern, in the lamp-post, or under the pavement.

The agent heretofore employed for elevating the oil from the reservoir is compressed air. This has been used in different ways, but with imperfect success, owing chiefly to the constantly diminishing pressure which the air exerts as its space is increased by the discharge of oil, and to the necessity for renewing the supply of air at short intervals, whereas the practical success of the system depends very much on long-continued automatic action. The use of atmospheric air is objectionable also, owing to the fact that it forms with the vapors of the light hydrocarbons an explosive or highly inflammable and offensive gas. The discharge of this, when a new supply of oil is to be introduced, is attended with more or less inconvenience and danger.

The present invention consists in the employment or use of water under pressure from the water-supply mains or service-pipes as means for elevating or feeding the oil, the operation to be governed by suitable cocks or valves. The invention consists further in means for discharging the water when a new supply of oil is to be introduced, and for preventing the escape of water when the supply of oil is exhausted, and for preventing the escape of oil with the water, and for securing the apparatus against being tampered with, as herein-after set forth.

The improved apparatus is simple, safe, and inexpensive; it involves the employment of no separate apparatus, as for compressing air or pumping in the oil; and it is applicable to the feeding of oil to burners for any purpose and in any location where a connection with a water-supply main or service-pipe can be made.

Figure 1 is an elevation of an ordinary lamp-

post with separate oil-supply apparatus attached beneath the pavement, illustrating this invention in a preferred form. Fig. 2 is a vertical section of the hydraulic oil-supply apparatus on a larger scale. Fig. 3 is a vertical section with plane at right angles to that of Fig. 2, showing the reservoir (in bucket-form) removed. Fig. 4 is an elevation on the same scale as Fig. 1, illustrating the arrangement of the improved oil-supply apparatus within the lamp-post. Fig. 5 is a partial vertical section of the same on a larger scale. Fig. 6 is a view, partly in elevation and partly in vertical section, illustrating the employment of an automatic valve to prevent the escape of oil, the same being applied to a modified form of underground or separate apparatus. Figs. 7 and 8 are vertical sections of other modified forms of underground or separate apparatus. Figs. 9 and 10 are vertical sections in different planes, representing an automatic valve for preventing the escape of water. Fig. 11 is a vertical section illustrating a modification of the mode of locking the apparatus shown in Figs. 1 and 2. Figs. 12 and 13 are, respectively, an elevation and a plan view illustrating other modified modes of locking the apparatus. Fig. 14 is an elevation illustrating a modification in which the oil-barrel or keg constitutes the reservoir, the oil being fed directly therefrom.

Like letters of reference indicate corresponding parts in the several figures.

The primary part of this apparatus is an oil and water tight reservoir, R, which for the general purposes of the invention may be of any approved form, construction, and size; but is preferably adapted to contain several gallons, so as to supply one or more burners with oil for a period of one or more weeks. A removable cap or cover, C, provides for filling the reservoir with oil. A pipe, W, connects the reservoir with a water-supply main or service-pipe, so that the pressure of the water within the main or pipe may be applied, directly or indirectly, to the oil. A second pipe, O, leads from the upper end of the reservoir, for conducting the oil to the burner B, which may be of any approved form.

In a preferred form of the apparatus (illustrated in Figs. 1, 2, 3, 6, 7, 8, and 14) the

invention is applied to the ordinary simple form of gas-lamp post L, Fig. 1, without any alteration thereof. The apparatus in this form is located beneath the pavement, at the foot of the lamp-post, in a well or vault, E, of sufficient size, as clearly illustrated in Fig. 1. A cast-iron box, B', may form the walls of this vault, and be provided with a removable flat cover, b, of circular or other form, similar to an ordinary sewer-trap cover. The lamp-post L, the box B', and the reservoir within the latter may be supported on stone or wooden sills A, Fig. 1, when necessary.

Where danger of freezing in winter does not exist, and new posts are required, the apparatus in simple form may be combined with the lamp-post L², as illustrated in Figs. 4 and 5, the reservoir being formed by an enlargement near the base of the post. In this form no well or vault whatever is required.

For shutting off the water when the reservoir is to be emptied and refilled with oil, a stop cock or valve, S, is provided in the water-pipe W. This cock may be of ordinary construction, and may be arranged at any convenient point; but by preference it is arranged within the well or box B' of the underground form of the apparatus, and furnished with an extended handle-rod, T, and it is arranged within the lamp-post L², above the ground level, in the other form of the apparatus, as illustrated. The flow of the water and oil may be regulated by means of this cock and the ordinary stop-cock S² at the burner, and this may be accomplished by making the cocks with passages of proper relative size.

For discharging the water when a new supply of oil is to be introduced a variety of means may be employed. In all cases the stop-cock S in the water-pipe is closed preliminary to this operation.

In the form shown in Figs. 1, 2, and 3 the reservoir R is removable, to provide for emptying it, and is inclosed and supported by a receptacle, R', to which the cap C and pipes W O are applied. The reservoir-bucket is constructed with feet z and a notch, y, so as not to obstruct the inlet and outlet openings, and the water has access to the bucket at bottom through orifices in a perforated cylinder, x, within which is a piston-valve, w, with stem v extending to the top of the bucket, where it is supported by a cross-bar, u. A hinged bail, t, facilitates handling the bucket. In elevated position, as shown in Fig. 2, the valve w is open. Depressed, the valve is closed, when the bucket, with its contents, may be removed, as illustrated by Fig. 3, the lid C being opened for this purpose. The removed bucket is emptied by opening the valve, and the discharge is stopped by closing the valve when oil is seen to escape. The bucket may then be filled with oil and replaced, or it may be replaced empty and then refilled. A small quantity of water or water and oil will be left in the receptacle R' when the bucket R is removed, but with ordinary care there will be no overflow.

With the refilled bucket in position and its valve w open the cap C is closed and secured, and the water-cock S is opened. The apparatus is then ready for use until the supply of oil is exhausted.

In the form of apparatus illustrated in Figs. 4 and 5 a simple discharge-cock, D, is applied to the bottom of the reservoir. This is opened and the contents are thus permitted to flow out into the street-gutter until oil is seen to escape, when the cock is closed. The cap C is then, or previously, removed, and oil is poured in thereat until the reservoir is full. The cap C is then replaced and the water-cock S reopened.

This mode of discharging the water may also be applied to any of the underground forms of the apparatus in places where the soil is sufficiently sandy to carry off the waste water.

To admit air above the discharging liquids in the reservoir a simple automatic valve, V, may be applied to a vent orifice in the cap C, as illustrated in Fig. 5, and this feature is applicable to any form of the apparatus in which a fixed reservoir is used.

In the form illustrated in Fig. 6 a discharge-cock, D, is applied to a pipe, W², extending upward from the water-pipe W, between the reservoir and the stop-cock S, and a portable pump is applied to the upper end of said discharge-pipe for drawing off the water.

In another modification of the apparatus the reservoir may be of sufficient size to supply several park-lamps, for instance; and, in this case, a sewer connection for carrying off the waste water may be provided. The escape of oil after the water in this form of apparatus may be prevented by an automatic valve, V², Fig. 6, applied to the orifice through which the discharge occurs, and this valve may consist of a ball, s, which will float in water, but not in oil, in combination with a seat, s', and cage r, as shown. A simple piston, I, to separate between the water and oil, may be employed, instead of this automatic valve, in a cylindrical reservoir, as illustrated in Fig. 7, and this will serve also to prevent the escape of water through the burner should the supply of oil be entirely exhausted before the reservoir is refilled.

In the form of apparatus illustrated in Fig. 8, a piston, I, to form the top of the water-space, is provided with a rod, q, extending through a stuffing-box, p, in the top of the reservoir, and having a cross-head, o, above the latter, to the ends of which springs n are attached, illustrating the application of one or more springs or weights to the piston as means for ejecting the water when the discharge-cock is opened. With this provision a short space is all that is required in connection with the discharge-cock to carry off the waste water from an underground apparatus.

In those forms of the apparatus in which a piston cannot readily be employed, as illus-

trated by Figs. 1 to 5, when means is desired for preventing the escape of water through the burner in the event of a failure to refill the reservoir before the oil is exhausted, an automatic valve, V^3 , may be introduced into the oil-pipe O , Figs. 9 and 10, at any point above the reservoir. In the form shown, this valve consists of a ball, m , Figs. 9 and 10, which will float in water, but not in oil, in combination with a flat circular case, l , having necks 1 2 at bottom and top, a valve-seat, 3, within the former, and a basket or cage, 4, formed by wires driven through from side to side to support the valve in proper proximity to its seat.

To secure the apparatus against being tampered with, in that form of the apparatus shown in Figs. 1, 2, and 3, the upper end of the stem T of the stop-cock S in the water-pipe, and the cap C at an adjoining point, are furnished with hasps k k^2 engaging with a single staple, j , to which a padlock, i , is applied. The hasp of the valve-rod T serves also as a handle for turning it.

A modification of this device is illustrated in Fig. 11. In this form a single hasp, k , with a bent extension, k^1 , is employed, in combination with a valve-rod having an ordinary cross-handle.

In that form of the apparatus shown in Figs. 4 and 5, the cap C , water-cock S , and discharge-cock D are all adapted to be turned by one and the same loose key, to be carried by the proper person.

A mode of locking up those forms of the apparatus, illustrated by Figs. 6, 7, and 8, is shown in Figs. 12 and 13. The means are analogous to those shown in Figs. 1 and 2, and consist of hasps k k^2 k^3 applied to the cap C , discharge-cock D , and valve-rod T , respectively, and a single staple, j , with which all engage, and to which a single padlock, i , Figs. 1 and 2, may be applied to secure the whole, the hasps serving also as lever-handles for the parts to which they are applied.

If preferred, the lock may be applied to the plate b , Fig. 1, by which the well of the underground apparatus is covered.

In the modification illustrated in Fig. 14 the barrel or keg in which the oil is received is employed in lieu of a distinct reservoir. The barrel is tapped in the ordinary way, and a cock, S , is inserted in the faucet-hole. The

barrel is then set in vertical position, the cock S is coupled to the water-pipe W , and the oil-pipe O is applied to the vent-orifice in the upper head. The water is then turned on by means of the cock S , and, under the control of the cock S^2 at the burner, the oil is fed to the latter as required.

At stated intervals the barrels or kegs will be removed and new or full ones attached, the former to be carted off with or without a previous discharge of the waste water.

The following is claimed herein as new, namely:

1. The combination of a street-lamp, an oil-reservoir, R , a pipe, W , for applying water under pressure from a water-supply main or service-pipe, and a pipe, O , for conducting the oil to the burner, substantially as herein described.

2. The combination of a street-lamp, an oil-reservoir, R , with cap C , a pipe, W , with stop-cock S , for applying water under pressure from a water-supply main or service-pipe, and a discharge-cock, D , for drawing off the water when the reservoir is to be refilled with oil, substantially as herein specified.

3. The combination of a street-lamp, an oil-reservoir, R , a water-pipe, W , an oil-conducting pipe, O , a discharge-cock, D , for drawing off the water, and a piston, I , to prevent the escape of either the water or the oil through the outlet of the other, substantially as herein set forth.

4. The combination of a street-lamp, an oil-reservoir, R , a water-pipe, W , an oil-conducting pipe, O , a discharge-cock, D , for drawing off the water, a piston, I , and one or more springs or weights applied to the latter for automatically ejecting the water when the discharge-cock is opened, substantially as herein shown and described.

5. The combination, with the reservoir R , and its cap C , and water-supply cock S , of the stem T applied to the latter, one or more hasps, k , a single staple, j , and a single padlock, i , for securing these parts in the manner set forth, so as to prevent tampering with the apparatus.

JAS. L. EWIN.
